UNDERGARMENT

David Blair, Chicago, Ill.

Application August 8, 1938, Serial No. 223,561

3 Claims.

(Cl. 2—30)

This invention relates to undergarments and more particularly to an improved brassière construction.

In the designing of brassières it is essential to provide a brassière construction which will support and maintain sagging breasts in an elevated and graceful position with a maximum of comfort to the wearer. It is well known that a brassière construction which does not support the breasts in the proper manner and which does not provide for ventilation thereof will often cause undue perspiration and irritation because the breasts are pressed tightly against the body of the wearer.

It is therefore an object of this invention to provide a brassière construction which will firmly and flexibly support sagging breasts in an elevated graceful position with discomfort to the wearer.

Another object is the provision of a brassière construction which will permit ventilation of the underside of the breasts.

A further object is the provision of a brassière construction which automatically serves to raise sagging breasts to a position free from contact with the body thereby preserving the fullness of the breast and causing some to assume a graceful position.

With the foregoing and other objects in view, the invention consists of the novel construction, combination and arrangement of parts as hereinafter more specifically described and illustrated in the accompanying drawing.

In the accompanying drawing

Fig. 1 is a perspective view of an undergarment embodying my brassière construction.

Fig. 2 is a detailed fragmentary enlarged rear view of the brassière construction shown in Fig. 1.

Fig. 3 is an enlarged cross sectional view of same taken on line 3—3 of Fig. 2 and showing same in full position such as when occupied by a breast.

The embodiment of the invention as illustrated in the drawing comprises a foundation garment 10 having two breast receiving pockets 11 and 12 incorporated in the upper front portion thereof. Said garment is provided with supporting shoulder straps 13 and conventional hose supporting members 14.

The breast receiving pockets 11 and 12 in accordance with this invention are each formed of an arcuate section 15 which is preferably of elastic open net material. The elastic is preferably extensible transversely and longitudinally. Se-

curement of said section to the body portion of the garment 10 is effected as by stitching along lines 16. Stitched to the upper edge of said section 15 along lines 17 is an inner concentric arcuate section 18. Said section 18, by reason of its securement to the arcuate section 15 which acts in the manner of a hinge, is adapted to project forwardly of the body portion 10 in an angular relationship therewith to assume substantially the configuration of a breast.

A semi-circular section 19 stitched to the upper edge of section 18 completes the lower portion of the breast receiving pockets 11 and 12. A member 20 stitched to the upper edge of the lower portion of breast pockets 11 and 12 serves as the upper portion of said pockets. Shoulder straps 13 hereinbefore described are secured to the upper edge of the member 20 and serve to support the garment 10 on the body of the wearer. A lining of net material, not shown, may be stitched to the under side of the breast pockets 11 and 12 to serve to protect the breast from contact with the seams of said pocket.

The action of this brassière construction will best be understood by reference to Figs. 1 and 3. It will be seen that when the garment 10 is extended transversely, such as when it is secured on the body of the wearer, the arcuate sections 15 are caused to be similarly extended. This transverse extension causes a decrease in the degree of curvature of the arcuate section 15, the tendency being to assume a straight line. There is, therefore, a definite elevation or lift of the lower portion 15a of the arcuate section 15. A corresponding elevation or lift is imparted to the arcuate sections 18 which causes the breasts to be raised so that their lower portions are free from the body.

In this construction the breasts are supported on the section 18 so that their lower portions are maintained out of contact with the body thereby elevating the breasts and preserving the fullness thereof and causing same to assume a graceful position. At the same time the open net construction of the arcuate section 15 serves to permit ventilation of the breasts. Since the breasts are supported out of contact with the body and at the same time ventilation provided therefor, undue perspiration and irritation is eliminated.

It will thus be seen that the brassière construction herein described firmly and flexibly supports the breasts in a natural and graceful position and also serves as a ventilating means for same, thereby adding to the comfort of the wearer.

While the brassière construction is shown incorporated in a garment of the corselet type, it will be apparent from the foregoing that a brassière, substantially of the same construction as 5 that hereinbefore described, can be used and worn independent of the corset portion.

It will be understood that while I have illustrated and described a preferred embodiment of my invention I do not wish to be limited to the 10 exact details disclosed herein but desire to avail myself of such variations and modifications as fall within the scope of the appended claims.

I claim

1. In an undergarment of the class described, a 15 body portion, breast receiving pockets, each of said pockets being formed of an upper and a lower portion, said portions being secured together throughout a line of jointure therebetween, said lower portion being formed of an 20 arcuate section and another section secured thereto throughout a line of jointure therebetween, said arcuate section secured to said body portion and said other section secured to said upper portion throughout lines of jointure there- 25 between, said lines of jointure extending across said pocket, said lower portion thereby being adapted to project forwardly relative to said body portion in angular relationship therewith to form a molded pocket and to cause the breast to be 30 supported in a desired elevated position, said arcuate section being formed of material characterized by relatively high elasticity and a substantially large mesh and adapted to permit the ventilation of the underside of the breast when 35 said undergarment is being worn.
2. In an undergarment of the class described, a body portion, breast receiving pockets, each of said pockets being formed of an upper and a lower portion, said portions being secured together throughout a line of jointure therebetween, said lower portion being formed of an 40

arcuate section and another section secured thereto throughout a line of jointure therebetween, said arcuate section secured to said body portion and said other section secured to said upper portion throughout lines of jointure there- 5 between, said lines of jointure extending across said pocket, said lower portion thereby being adapted to project forwardly relative to said body portion in angular relationship therewith to form a molded pocket and to cause the breast to be 10 supported in a desired elevated position, said arcuate section being formed of material characterized by relatively high elasticity adapted to be stretchable in the direction of its length, throughout the length of the section, transversely 15 of the body of the wearer, said arcuate section when so extended arranged to provide additional elevation for the breast.

3. In an undergarment of the class described, a body portion, breast receiving pockets, each of 20 said pockets being formed of an upper and a lower portion, said portions being secured together throughout a line of jointure therebetween, said lower portion being formed of an arcuate section and another section secured thereto throughout 25 a line of jointure therebetween, said arcuate section secured to said body portion and said other section secured to said upper portion throughout lines of jointure therebetween, said lines of jointure extending across said pocket, said lower 30 portion thereby being adapted to project forwardly relative to said body portion in angular relationship therewith to form a molded pocket and to cause the breast to be supported in a desired elevated position, said arcuate section being 35 formed of material characterized by relatively high elasticity adapted to be stretchable both in the direction of its length, transversely of the body of the wearer and in the direction of its width, longitudinally of the body of the wearer. 40

DAVID BLAIR.

CERTIFICATE OF CORRECTION.

Patent No. 2,180,391.

November 21, 1939.

DAVID BLAIR.

It is hereby certified that error appears in the printed specification of the above numbered patent requiring correction as follows: Page 1, first column, line 18, for the word "with" read without; and that the said Letters Patent should be read with this correction therein that the same may conform to the record of the case in the Patent Office.

Signed and sealed this 16th day of January, A. D. 1940.

Henry Van Arsdale,

(Seal)

Acting Commissioner of Patents.
